UNITED STATES PATENT OFFICE.

WILLIAM GESSNER, OF WEST HOBOKEN, NEW JERSEY.

HOLDER FOR PLAYING-CARDS.

1,109,524.

Specification of Letters Patent. Patented Sept. 1, 1914.

Application filed February 10, 1914. Serial No. 817,836.

To all whom it may concern:

Be it known that I, WILLIAM GESSNER, a citizen of the United States, residing at West Hoboken, in the county of Hudson, 5 State of New Jersey, have invented certain new and useful Improvements in Holders for Playing-Cards; and I do hereby declare the following to be a full, clear, and exact description of the invention, such as will 10 enable others skilled in the art to which it appertains to make and use the same.

The present invention is directed to improvements in holders for playing cards, and has for its object to so construct a device 15 of this character that a number of cards dealt to a player can be conveniently held in spread positions so that the denominations of the cards can be ascertained at a glance.

20 A further object of the invention is to provide a holder of this type so constructed that the cards can be easily and quickly removed from the holder during the playing of the game.

25 With these and other objects in view, this invention resides in the novel features of construction, formation, combination and arrangement of parts to be hereinafter more fully described, claimed and illustrated in 30 the accompanying drawing, in which:—

Figure 1 is a rear elevation of the device. Fig. 2 is a front view. Fig. 3 is a sectional view on line 3—3 of Fig. 1. Fig. 4 is a similar view on line 4—4 of Fig. 1.

35 The holder consists of a handle 1 which supports the frame 2, said frame consisting of a single length of wire so bent as to provide horizontal bars 3, the ends 4 of which being fixed in the handle 1. The outer ends 40 of the bars 3 terminate in upwardly inclined arms 5 which are connected by the upwardly curved bar 6. The holder further consists of an arcuate plate 7, the same being formed from sheet metal and has its end edges pro- 45 vided with sleeves 8 which engage the arms 5, thus firmly connecting the plate to the frame 1. The lower edge of the plate 7 is

provided with an inwardly directed continuous flange 9 which limits the movement of the playing cards in a downward direction 50 when the same are engaged between the bar 6 and inner surface of the plate 7.

From the foregoing description it will be seen that when a player is dealt a hand, the cards can be readily inserted between the 55 bar 6 and plate 7 and quickly spread in a fan like position so that the denominations of the cards can be readily ascertained when the device is grasped by the handle 1.

The plate 7 is slightly curved throughout 60 its length so that when the cards are engaged in the holder the same will be held curved transversely and in a manner usually employed when holding the cards in the hand. 65

What is claimed is:—

1. A holder for playing cards comprising a wire frame, said frame including a curved bar, an arcuate plate supported by the frame and coacting with the bar to hold cards 70 therebetween, and means carried by the plate to limit the downward movement of the cards.

2. A holder for playing cards comprising a handle, a wire frame formed from a single 75 length of wire and being bent to provide horizontal bars, the inner ends of said bars being connected to the handle, the outer ends of said bars terminating in upwardly inclined arms, a curved bar connecting said 80 arms, an arcuate sheet metal plate having its end edges provided with sleeves for engaging the inclined arms, the lower edge of said plate being provided with an inwardly directed continuous flange for engagement by the lower end edges of the cards when the same are engaged between the curved bar and plate. 85

In testimony whereof, I affix my signature, in presence of two witnesses.

WILLIAM GESSNER.
